UNITED STATES PATENT OFFICE.

JAMES W. KNOBLOCK, OF ELMIRA, NEW YORK, ASSIGNOR TO AMERICAN LA FRANCE FIRE ENGINE CO., INC., OF ELMIRA, NEW YORK, A CORPORATION OF NEW YORK.

PORTABLE ELECTRIC HAND-LANTERN.

1,341,471.

Specification of Letters Patent.

Patented May 25, 1920.

Application filed June 19, 1917. Serial No. 175,626.

To all whom it may concern:

Be it known that I, JAMES W. KNOBLOCK, a citizen of the United States, residing in Elmira, in the county of Chemung and State 5 of New York, have invented certain new and useful Improvements in Portable Electric Hand-Lanterns, of which the following is a full and clear specification.

The object of the present invention is to 10 provide an improved construction of portable hand lanterns, having storage battery cells for supplying the current. In general construction the improved lantern comprises a metal container supporting two electric 15 storage battery cells and having means to insure the proper arrangement of the cells in series formation; a light projecting reflector supported mainly within the container between the battery cells; suitable 20 adjustable devices mounted upon the rear wall of the container and projecting therefrom toward the reflector to focus and support the electric lamp in proper relation to the reflector; a hand operated switch inter- 25 posed between the lamp and battery cells; and a cover for the lantern container carrying suitable contact plates which automatically contact with the spring terminals of the battery cells and the hand operated 30 switch when the cover is secured in closed position, it being preferable to hinge the cover to the container body and provide a hasp or other suitable device for securing it in closed position.

35 The present invention comprises structural features of the general nature referred to to facilitate the economical manufacture and efficient operation of hand lanterns of the type referred to.

40 In order that the invention may be fully understood I will first describe the same with reference to the accompanying drawings and afterward point out the novelty more particularly in the annexed claims.

45 Figure 1 is a vertical longitudinal sectional view of a hand lantern embodying my improvements;

Fig. 2 is a partial rear view of the same, parts of the interior arrangement being represented in dotted lines;

50 Figs. 3 and 4 are enlarged detail views of the device for locking the glass retaining bezel in place upon the lantern;

Fig. 5 is a top plan view of the improved lantern with the cover member removed; 55

Figs. 6 and 7 are detail views illustrating a modified form of lamp supporting socket; and

Figs. 8 and 9 are respectively a top plan view and side elevation of the lamp cover, 60 showing the handle bail and hook devices.

1 is a sheet metal casing or container of general rectangular configuration formed with a reinforced bottom 2, an open top 3 (closed by a cover hereinafter referred to) 65 a vertically elongated central depression or recess 4 in the back wall, and a circular inwardly flanged rim 5 projecting slightly from the front wall to form a support for the lamp reflector and the protecting lens 70 or front glass.

An internal metal brace, shown at 10, projects from side to side of the lamp casing a short distance from the bottom and is riveted by its angular ends 11 to the side 75 walls of the casing. This metal brace 10 has a central rearwardly extended portion, as shown at 12, to form, in conjunction with the rear corner portions and depression 4 of the casing, upright pockets for the reception of two storage battery cells, which are indicated at 15. These cell pockets are arranged at opposite sides of the lamp casing with proper space between them to receive the circuit controlling switch, the bulb supporting socket extending rearwardly from the center of the reflector and circuit wires and bulb adjusting devices. The arrangement of the storage battery cells at opposite 80 sides of the lamp as described produces a 85 nicely balanced structure.

The battery cells 15, 15, may be of any approved construction. Each cell is preferably provided with positive and negative terminals in the form of compressible spring 95 contacts, such as 16, which are designed to contact with connector plates or strips mounted upon the inner face of the cover hereinafter described. A lug 17 projects from the forward face of each cell 15 to insure against placing the cells in the lamp casing in improper position, said lugs engaging the rear wall of the casing in the event of an attempt to place them therein in reversed position.

20 is the ordinary concave reflector

formed with an annular flange 21, which is presented within the inwardly flanged rim 5, to which it is rigidly secured by rivets or screws and nuts. Since the flanged rim 5 projects over the edge of the reflector 20, it will be understood that an effective spray proof joint between the two is obtained.

25 is the glass-securing bezel formed with a deep circular ring 26, which snugly fits 10 the rim 5 of the casing by which it is supported. This bezel ring 26 is formed with inclined slots 27, leading in from its rear edge which engage set screws 28 threaded into the rim 5. Interlocking slots 27 and 15 screws 28 are arranged at irregular intervals around the circumference of the bezel ring 26, so as to insure placing the bezel in proper position on the lamp. Upon one edge of the bezel ring (preferably adjacent 20 to the bottom where it is out of the way and inconspicuous) is formed an offset eccentric portion 28, having in its inner edge ratchet teeth 29, with which engages a dog 30, formed upon a spring plate 31, secured to 25 the front of the lamp casing at 32. The dog 30 in engagement with the ratchet teeth 29 securely locks the bezel ring in position upon the lamp, so that it cannot accidentally come loose and fall off.

30 35 is the protecting glass or lens, secured in the open front of the reflector 20 by the bezel 25 just described. A rubber gasket 36 rests between rim 5 and glass front 35. This glass front 35 holds in place an up- 35 right narrow strip of glass 40, upon the upper end of which rests a spring contact arm 41 held normally in electrical contact at 42 with a circuit plate 43, hereinafter referred to. The contacts 42 and 43 are connected up with the switch terminals of the 40 lamp in the manner to be explained, the purpose of the automatic switch controlled by the supporting safety glass being to provide a means for automatically breaking 45 the lamp circuit in the event of an accidental fracture of the protecting glass front in the presence of an explosive gas or other material. In the event of such an accident, the safety glass being fractured, 50 will release the spring contact arm 42, which will automatically move away from the contact plate 43 and break the lamp circuit so that there can be no glowing of the lamp filament or other circuit parts, 55 therefore the danger of explosion from this cause is eliminated.

The reflector 20 is provided, as usual, with a central socket or opening 20^a in which is mounted a flanged collar 45, carrying a set 60 screw 46, which engages a second collar 47, mounted concentrically within the collar 45, and projecting rearwardly and formed at its inner end with a slightly contracted throat 48, in which is mounted a cylindrical 65 lamp socket 50 containing the usual internal

arrangement of contacts and wires. The socket 50 is formed with bayonet joint slots 51, with which engage the oppositely projecting pins 52, projecting from the base of the electric bulb 53. The lamp supporting socket 50 is freely fulcrumed in the contracted throat 48 and has ample clearance in the forward end of the supporting collar 47, so that it can rock freely up or down or sidewise or at any angle from the center line of the reflector, in order to centralize the lamp filament with the reflector. This mounting of the lamp socket also permits the adjustment of the lamp either forward or backward within the reflector to obtain a proper focus in the reflector, for making either a concentrated beam of light or a wider spread of light, as may be desired.

55 is a yoke or cup-shaped member open 85 at the top to permit the entrance of circuit wires to the socket 50 and closely engages the rear end of the socket 50. This member 55 is mounted upon the inner end of a screw stem 56, threaded through a sleeve 57 90 provided at its outer end with a securely fastened knurled head 58 and at its inner end with a collar 59, confining a spring washer 59^a against the head 61 to frictionally hold sleeve 57 in position. The sleeve 57 95 rotates freely in a concentric sleeve 60, formed with an inner head 61, engaging the inner face of the inset plate 62 (hereinafter referred to) the sleeve 60 passing through the enlarged opening 63 of plate 100 62 and carrying at its outer end the milled clamping nut 64, which engages the outer face of plate 62 and the clamping nut 65, which engages the nut 64. Nuts 64 and 65 are threaded upon the sleeve 60.

The inset plate 62 is secured upon the inner face of the wall of depression 4 of the lamp casing, above referred to. This depression 4 has an opening 4^a cut through its inner wall and the inset plate 62 has a shallow dished or spheroidal portion 62^a, which rests in the cut out 4^a directly behind the central axis of reflector 20. This inset plate 62 is secured to the metal casing by means of set screws shown at 67.

From the described construction of adjustable bulb supporting devices it will be understood that by loosening the nuts 64 and 65 the screw stud 56 can be shifted up or down or sidewise or at any angle in the lamp casing, carrying with it the lamp socket 50 and bulb 53, the socket being fulcrumed in the throat of the collar 47. When the bulb is properly centralized in the reflector 20, the nuts 64 and 65 are 125 tightened to retain this adjustment. Then by means of the knurled head 58 the sleeve 57 can be rotated to move the screw stem 56 and connected socket 50 inwardly or outwardly to get the desired focus.

The structure of the focusing device for the electric projector is not claimed in the present application, but forms the subject matter of my divisional application filed 5 March 22nd, 1918, Serial No. 223,963.

The inset plate 62 also carries above the bulb adjusting devices, just described, a push switch of suitable construction, represented at 70 and provided with an operating handle 71. This switch has connected with one of its terminals 81 the circuit wire, 80, leading from the socket 50 and to its other terminal 82 the spring contact arm 42, above referred to, making the electric 15 circuit from the plate 43 through arm 42, terminals 82, 81, circuit wire 80, into the lamp supporting socket. A second circuit wire 85 leads from lamp socket 50 up to a binding post 90 mounted upon a block of insulating material 91, secured to plate 62, above switch 70. A second binding post 95, mounted upon the block 91, has connected with it an extension 43^a from the contact plate 43 of the automatic switch above referred to.

The binding posts 90 and 95 are provided with suitable compression spring contacts 90^a and 95^a, similar to the contacts 16 of the storage battery cells above referred to, said 30 spring contacts being designed to coöperate with suitable contact plates carried by the lamp cover, which will now be explained.

100 is a sheet metal cover adapted to snugly fit upon the open top of the lamp 35 casing. This cover 100 is hinged at 101 upon one side of the casing and is provided at its opposite side with a hinged hasp 102, adapted to engage staple 103 arranged to receive a bolt of a suitable lock for securing 40 the cover in closed position.

Upon the inner face of the cover 100 is arranged suitable contact plates which are insulated from the cover and designed to make contact with the battery terminals and 45 switch binding posts, above referred to. One of these contact plates shown at 105, extends from side to side of the lamp casing, directly above the forward battery terminals 16, of the two cells and makes electrical contact with said spring contacts of 50 said cells. This contact plate 105 is secured to the lamp cover by means of bolts 106, passing through flanged insulating washers 107 which are seated in suitable openings in 55 a plate of insulating material which extends the width of the cover. Two of these fastening devices are provided for the plate 105.

Extending across the lamp cover near its rear edge there are two contact plates 110, 60 111, of a similar construction, each plate terminating approximately in the center of the cover and being secured to the inner face of the cover by suitably insulated bolts 112 of the same general construction as just 65 described with reference to plate 105. These

contact plates 110 and 111 are so arranged that one contact plate makes electrical connection between the binding post 90 and one of the rear terminals 16 of a battery cell while the other contact plate makes electrical contact between the other binding post 95 and the rear terminal 16 of the other battery cell.

The two storage battery cells are designed to operate in series and to this end the projecting lug 17 upon the front of each cell prevents the improper insertion of the cells in the casing and thereby insures the proper arrangement for the series operation. The electric circuit is made from one binding 75 post through the connected battery cells to the other binding post; the remainder of the circuit through the automatic and hand switches and lamp being as above explained.

For convenience in carrying the lamp and 80 hanging it up, when desired, I have provided a combined handle bail and hook shown particularly in Figs. 8 and 9 of the drawings, the handle bail 120, consisting of an ordinary metal wire loop having its 85 turned ends 121 journaled in the sheet metal socket pieces 125, riveted to the top of the cover 100. This bail operates in the usual manner.

Coöperating with the loop bail referred 90 to is an adjustable hook consisting of a swiveled bar 130 freely journaled in the inner socket portions of members 125 and formed between its ends with a flattened perforated and widened web portion 131, 100 through which extends the headed rod 135, of a rectangular hook member 136. The head 137 of the hook member is designed to rest in the flattened or expanded swivel portion of the bar 130 when the hook is in 105 operation.

The combined bail and hook handle is not claimed in the present application, but forms the subject matter of my divisional application upon which Patent 1,301,574 110 was granted April 22nd, 1919.

In Figs. 6 and 7 of the drawings I have shown a simple arrangement of devices for supporting the incandescent lamp socket within the reflector. In this form of device 115 the reflector 20^a is formed with an integral split collar 20^b, which is surrounded by a split collar 150 provided with a set screw 151 passing through the adjacent walls of the collar for binding it upon the reflector 120 collar 20^a. The lamp supporting socket 50^a, carrying the bulb 53^a fits snugly within the reflector collar 20^b and is clamped in the desired adjusted position therein by means of the set screw 151. The circuit wires extending from lamp socket 50^a are the same as described above in connection with the preferred form of the device.

Among the important advantages resulting from the improved construction, atten- 130

tion is directed to the general arrangement of parts with the location of the two secondary battery cells at opposite sides of the lamp, providing ample room for the convenient location of the switch and contact mechanism between the cells in the rear of the reflector. This arrangement permits the employment of a relatively large reflector, since the rear portion is offered room between the battery cells. The arrangement is such that the battery cells can be placed in the lamp only in the proper operative relation. Each cell is provided with means to prevent its improper insertion in the lamp casing. The fastening of the reflector within the casing from the inside with the overlapping casing flanges is of importance with reference to making the lamp moisture proof. The bezel lock is important in holding the bezel against accidental displacement. The mounting of the contact terminals, switch and bulb adjusting devices upon a common supporting plate at the rear of the lamp enables these parts to be removed as a whole, for adjustment and repair, by simply disconnecting the supporting plate and the proper contacts.

I claim:

1. In a portable electric hand lantern, the combination of a casing having spaced cell pockets arranged at opposite sides, the back wall of said casing having a central inwardly depressed portion forming an inner spacing member between the cell pockets and an outer recess for hand operated parts, battery cells in said pockets, a reflector mounted in the front wall of the casing, a light bulb mounted within the reflector, and a switch mounted upon the back wall of the casing with its operating head presented in the recess of said depressed portion.

2. A portable electric hand lantern comprising a suitable casing formed with two centrally separated cell pockets, battery cells mounted in said pockets, a reflector mounted in the front wall of said casing, a lamp bulb, and bulb adjusting and circuit controlling devices mounted in the rear of said reflector between said cells.

3. A portable hand lantern comprising a suitable casing having spaced and balanced cell pockets, battery cells mounted in said pockets, a reflector mounted in the front wall of said casing, adjustable bulb supporting devices mounted upon the casing in rear of said reflector in the space between said cells, and a controlling switch also mounted upon said casing between said cells and in electric circuit with said cells and bulb.

4. In a portable electric hand lantern, the combination of a casing having a central inward projection on its back wall, a partition bar extending transversely of the casing and having a central rearwardly projecting portion arranged opposite to the back wall pro-

jection and forming therewith spaced cell pockets in opposite sides of the casing, battery cells arranged in said pockets, a reflector mounted in the forward wall of the casing, a light bulb, a switch, and suitable circuit connections including the battery cells, the bulb and switch. 70

5. In a portable electric hand lantern, the combination of a casing having a central inwardly depressed back wall portion, a bar 75 extending transversely of the casing and formed with a central rearwardly bent portion arranged opposite to the depressed back wall portion to form spaced cell pockets upon opposite sides of the casing, battery 80 cells arranged in said pockets, a reflector mounted in the forward wall of the casing and projecting rearwardly into the space between said cell pockets, a switch upon the depressed back wall portion, a light bulb, 85 and suitable circuit connections including the battery cells, the switch and bulb.

6. A portable electric hand lantern comprising a suitable casing formed with cell 90 pockets, battery cells mounted in said pockets and a reflector mounted in the front wall of said casing, each battery cell being provided upon one of its walls with an outwardly projecting lug adapted to prevent the improper insertion of the cell in a 95 pocket.

7. In a device of the character described, the combination of a suitable casing having cell pockets, battery cells mounted in said pockets, a lamp reflector mounted in the 100 front wall of said casing, a bulb, a depression formed in the rear wall of the casing, and a circuit controlling switch mounted between the reflector and said depression with its operating head resting in the depression 105 within the plane of the rear wall of the casing.

8. In a device of the character described, the combination of a suitable casing having cell pockets, battery cells mounted in said 110 pockets, a lamp reflector mounted in the front wall of said casing, an adjustably mounted light bulb, a depression formed in the rear wall of the casing, a circuit controlling switch mounted between the reflector and said depression, and suitable bulb adjusting devices also mounted between the reflector and said depression, the operating heads of said switch and bulb adjusting devices resting in the depression within the 115 plane of the rear wall of the casing.

9. In a device of the character described, the combination with a lamp casing having cell pockets, battery cells mounted in said 125 pockets, a reflector mounted in the front wall of said casing, a lamp bulb coöperating with said reflector, a circuit controlling switch, suitable bulb adjusting devices, the rear wall or lamp casing having a cut out portion, and a removable inset plate mount- 130

ed in said cut out portion, said switch and bulb adjusting devices being mounted upon said inset plate and removable therewith from the casing as a unit.

- 5 10. In a device of the character described, the combination with a lamp casing having cell pockets, battery cells mounted in said pockets, a reflector mounted in the front wall of said casing, a lamp bulb coöperating with said reflector, a circuit controlling switch having contact terminals, suitable bulb adjusting devices, and suitable circuit connector plates extending between the battery cells and the switch terminals, the rear 15 wall or lamp casing having a cut out portion and a removable inset plate mounted in said cut out portion, the said switch, the

contact terminals and bulb adjusting devices being mounted upon said inset plate and removable therewith from the casing as 20 a unit.

11. A suitable casing carrying upon its front wall a rearwardly projecting reflector, an inwardly depressed rear wall portion forming a recess or cavity, battery cell 25 pockets arranged in opposite sides of the casing with parts of said reflector and depressed wall between them, bulb adjusting and circuit controlling devices mounted between the wall depression and reflector and 30 between the cell pockets, and battery cells mounted in said pockets.

JAMES W. KNOBLOCK.
